Specification for Design.

Patented Nov. 29, 1921.

Application filed March 31, 1921. Serial No. 457,526. Term of patent 14 years.

To all whom it may concern:

Be it known that we, ELMER L. SCHUMACHER and WILLIAM H. BOUTELLE, citizens of the United States, residing at Southbridge, in the county of Worcester and State of Massachusetts, have invented a new and original ornamental Design for a Frame Member of an Ophthalmic Mounting, of which the following is a specification, reference being made to the accompanying drawings, forming a part thereof.

Figure I represents a front view of our novel design for an ophthalmic mounting.

Fig. II represents a plan view thereof.

Fig. III represents an edge or end view of the same.

We claim:

The ornamental design for a frame member of an ophthalmic mounting, substantially as illustrated.

In testimony whereof, we affix our signatures in the presence of two witnesses.

ELMER L. SCHUMACHER.
WILLIAM H. BOUTELLE.
